DESIGN FOR AN ASHTRAY

William E. Mackelfresh, Jr., Chicago, Ill., assignor to Owens-Illinois Glass Company, Toledo,
Ohio, a corporation of Ohio

Application July 15, 1936, Serial No. 63,856

Term of patent 7 years

To all whom it may concern:

Be it known that I, William E. Mackelfresh, Jr., a citizen of the United States, and residing at Chicago, in the county of Cook and State of Illinois, have invented a new, original, and ornamental Design for an Ashtray, of which the following is a specification, reference being had to the accompanying drawing, forming a part thereof.

In the drawing:

Fig. 1 is a perspective view of an ashtray showing my new design.

Fig. 2 is a top plan view thereof.

I claim:

The ornamental design for an ashtray substantially as shown.

Signed at Toledo, in the county of Lucas and State of Ohio, this 9th day of July, 1936.

WILLIAM E. MACKELFRESH, JR.
